R. Montgomery,

UNITED STATES PATENT OFFICE.

RICHARD MONTGOMERY, OF NEW YORK, N. Y.

MODE OF CONSTRUCTING A COMBINED STREET-PAVEMENT AND RAILROAD-TRACK.

Specification of Letters Patent No. 22,665, dated January 18, 1859.

To all whom it may concern:

Be it known that I, RICHARD MONTGOMERY, of the city and county of New York, in the State of New York, have invented a new and useful Improvement in Combined Street-Pavements and Railroad Tracks; and I do hereby declare that the following is a full description thereof.

To enable others skilled in the art to which 10 my improvement belongs to construct and use my improvement, I will now proceed to describe the same, reference being had to the annexed drawings and to the letters of reference marked thereon, forming a part of this 15 specification.

Figure 1, represents a perspective view of one of the arches of my combined street pavement and rail road track; Fig. 2, is a similar view, the only difference between 20 Figs. 1, and 2, being that in Fig. 2, the arch is represented to span the whole width of the street from curbstone to curbstone, while in Fig. 1, the arch covers only part of the width of the street between the curbstones; 25 Fig. 3, exhibits a section across one of the arches, on a large scale; Fig. 4, is a perspective and Fig. 5, an end view representing modifications of the arrangement of the track as shown in Figs. 1, 2, and 3.

20 A, B, C, D, represent one of the arches which when put together constitutes a continuous street pavement and rail road track. These arches consist of parallel corrugations a, a, a, which are intersected by two or more 25 rail tracks b, b, the rails and corrugations being cast in one piece. The bottom part of the arches is provided with projections d, d, at suitable distances from each other, for the purpose of strengthening the central portion 40 of the arches between the rails b, b.

Figs. 1, and 2, represent hollow rails, suitable for city railroads; Fig. 5, represents a dovetailed rail suitable for the insertion of a raised rail c, as shown in Fig. 4. 45 f, f, are the curbstones and e, e, in Fig. 1, represents the street pavement in common use.

The foundation of the arches is formed of concrete g, g. The spaces between the corrugations may also be filled with concrete as seen at h, h, Fig. 3.

The projections d, d, instead of extending across the track as seen in Figs. 1, 2, and 3, may be arranged in line with the rails b, b, 55 as represented in Fig. 4. The arches how-

ever can be laid on common light soil without the use of any concrete.

One great objection to the introduction of rail roads into cities and large towns arises from the difficulty and expense of 60 keeping them in proper repair. In all cases where the street has to be repaved or where the pavement needs repairs, it cannot be done without disturbing the track. Neither can the track be repaired without disturbing to a greater or less degree, the street pavement. Again, in most cases, the rails are continually liable to be displaced by the settling or displacement of one or more stones or blocks of the street pavement. By adopting my plan of a combined street pavement and rail road track, all or nearly all of these 65 objections are obviated. That this is the case, will be apparent when it is remembered that my pavement and track are cast together. So far as the pavement is concerned, it resembles my improved street pavement, for which I have applied for Letters Patent. It is formed of parallel arched corrugations, 70 said corrugations being cast thicker on the top than on the bottom as seen at a, a, Fig. 3. These corrugations may extend on either side of the grooved track b, b, to the curbstones f, f, as represented in Fig. 2. In laying this track however, in streets which are 75 now paved, it may be best perhaps, to let it extend but a short distance on either side of the track (as seen in Fig. 1,) as by this mode of construction a good footway will be obtained in the center of the street for horses, 80 while at the same time a sufficient amount of surface of the pavement will come in contact with the ground to render the pressure on any one point, under the heaviest loads, 85 but trifling, when compared to what it would be, if the track and pavement were separate. 90

In laying my combined pavement and rail road track, no sleepers are required, and the sections are laid at once upon the prepared ground or roadway, the projections d, d, answering the purpose of sleepers. As no sleepers are used, there is none to be repaired, consequently, when a track after 95 my plan is once laid, it will last for years with but little liability to get out of order.

In most cases it will be found unnecessary to add or use wrought iron rails, the flanges of the wheels running in the grooves b, b, cast for that purpose on the upper face of the pavement. If however it should be de- 100 105 110

sired, wrought rails may be run into the grooves cast on the upper face of the pavement, as represented in Fig. 4. The grooves in such cases can be cast of any suitable form. 5 Figs. 4, and 5, represent grooves of a dove-tailed form. As a general thing, however, I contemplate casting the groove for the flange of the wheel, as well as the face or rail for the tread of the wheel all as fully shown 10 in Figs. 1, and 2. It will be observed, that the projections *d*, cast upon the under surface of the pavement answer the purpose of holding the pavement and track in place, and at the same time add strength to 15 the whole. I am thus enabled to combine a pavement and rail road track in such a way as to lessen the cost and expense of city rail roads nearly one half. It will also be seen that I obviate the necessity of a hard and 20 solid roadway prior to the laying of the pavement, while by the use of the arched form of the corrugations, any pressure upon the upper surface of the track and pavements has a tendency to force the soil or 25 earth under the pavement up toward the center of the track or pavement, that being the highest point, and thus the whole structure is, by the pressure of the vehicles etc., which pass over it, retained in an even and 30 properly balanced position--a feature of

great importance in a practical point of view. Again the grooves and rails for the wheels of the cars, afford a foothold for horses, when crossing the streets or when about to start with a load from a store etc., 35 but as the track is firmly united to the pavement, both being cast together, there is no danger of the rails or the track being displaced by such strains upon them, however severe. 40

Only one track has been shown in the annexed drawings, but it is apparent that any number can be used and that too without a departure from the principle of my invention. 45

The arches (of which the drawings represent one, A B C D,) may be united by dove-tails or in any other suitable way.

Having described my combined pavement and track, what I claim therein as new and 50 of my invention, and desire to secure by Letters Patent, is—

A combined street pavement and rail road track, constructed substantially as shown and described.

R. MONTGOMERY.
